INVENTOR

Charles F. Redlich,
by his atty J. H. Hubbard,

UNITED STATES PATENT OFFICE.

CHARLES F. REDLICH, OF BROOKLYN, NEW YORK.

DESIGN FOR A POWDER-SPRINKLER.

SPECIFICATION forming part of Design No. 21,103, dated October 6, 1891.

Application filed July 24, 1891. Serial No. 400,655. Term of patent 7 years.

To all whom it may concern:

Be it known that I, CHARLES F. REDLICH, a citizen of the United States, residing at Brooklyn, in the county of Kings and State of New York, have invented and devised a new and original Design for Powder-Sprinklers, of which the following is a specification, reference being had to the accompanying drawing, which forms a part thereof, and which shows

10 in elevation a powder-sprinkler in accordance with my design.

The leading features of my design consist of the cylindrical body and the top having the slender neck 6, surmounted by the spherical head 8, and the curves 4, 5, and 7, which give to the cover its peculiar outline.

In the drawing, 1 is the body of the powder-sprinkler, cylindric in its form, its length be-

ing slightly greater than its diameter. It has a flanged base consisting of the curves 2 and 3. The cover or top is of irregular shape, but of approximately conoidal outline, consisting of the curved lines 4, 5, and 6, the bead 7 between the lines 5 and 6, and the sphere 8 upon the apex of the cover.

20 I claim—

The design for powder-sprinklers and the like, substantially as herein shown and described.

25 In testimony whereof I affix my signature in presence of two witnesses.

CHARLES F. REDLICH.

Witnesses:

GEORGE SPERRY,
JOHN ENSENROTH.
